United States Patent Office

Des. 200,308
Patented Feb. 16, 1965

200,308

CHAIR

Leo H. Klausen, 338 Hillcrest Ave., Willowdale,
Ontario, Canada

Filed Sept. 30, 1963, Ser. No. 76,801

Term of patent 14 years

(Cl. D15—1)

FIG. 1

FIG. 2

FIG. 1 is a perspective view from the front and to one side of a chair showing my new design; and

FIG. 2 is a perspective view from the rear and to one side thereof.

The side not shown is the same in appearance as the side shown.

I claim:

The ornamental design for a chair, as shown and described.
